CLAIM

The ornamental design for a rocking chair frame, as shown and described.

DESCRIPTION

FIG. 1 is a front view of the rocking chair frame showing my new design;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is a perspective view thereof; and,

FIG. 8 is another perspective view thereof.

The broken line showing of the seat of the rocking chair frame in FIG. 8 is for the purpose of illustrating environmental structure and forms no part of the claimed design. The broken line in FIG. 6 depicts portion of the rocking chair frame that forms no part of the claimed design.
